APPARATUS FOR CONTROLLING
REFRIGERATING SYSTEMS

Edward F. Dickieson, Jr., Detroit, Mich.; Nathalie L. Dickieson, executrix of said Edward F. Dickieson, Jr., deceased, assignor to Nathalie L. Dickieson

Application February 4, 1949, Serial No. 74,586

5 Claims. (Cl. 62—6)

1

This invention relates generally to method and apparatus for controlling refrigerating systems and is an improvement upon my copending application, Serial No. 750,947 filed May 28, 1947, for Control Mechanism.

An object of this invention is to provide a new and improved method of and apparatus for controlling the operation of refrigerating systems.

Another object of this invention is to provide such a system in which the controlling apparatus is governed at least in part by the temperature of the refrigerated space.

Another object of this invention is to provide such a refrigerating system in which the operation of the compressor is controlled by means of the temperature of the enclosed space.

Another object of this invention is to provide in such a system means for maintaining the operation of the compressor continuous.

Another object of this invention is to provide a new and improved control apparatus for use with the refrigerating system.

Other objects of this invention will be apparent from the appended claims, the specification and the drawings in which drawings:

Figure 1 is a diagrammatic view of a refrigerating system embodying the invention and showing the control apparatus in enlarged central vertical section;

Fig. 2 is a view showing the temperature control dial for use with the control apparatus;

Fig. 3 is substantially a quarter section view showing a modified control apparatus for use in the system of Fig. 1;

Fig. 4 is a view taken substantially along the line 4—4 of Fig. 3;

Fig. 5 is a view in central vertical section showing a still further modified form of control apparatus for use in the system of Fig. 1;

Fig. 6 is a schematic view of a modified form of refrigerating systems embodying a modified form of the control apparatus;

Fig. 7 is a view in substantially vertical central section of the control elements of Fig. 6;

Fig. 8 is a view in central vertical section of the working cylinder illustrated in Fig. 6 which positions the speed controlling element;

Fig. 9 is a view similar to Fig. 7 but showing a modified form of control apparatus in which the working cylinder is fabricated integrally with the control apparatus;

Fig. 10 is a view taken substantially along the line 10—10 of Fig. 9;

Fig. 11 is a view in quarter section showing a still further modified form of the control apparatus for use in the system of Fig. 6; and

2

Fig. 12 is a view taken substantially along the line 12—12 of Fig. 11.

Referring to the drawings by characters of reference, like numerals are used to designate like parts in the several views illustrating the same modification and used with subindices to designate corresponding parts in the several modifications. The numeral 10 indicates generally a space to be refrigerated which is provided with an evaporator 8 operatively connected with a condensing unit controlled by means of a control apparatus 18.

Basically the invention contemplates a refrigerating system comprising the usual compressor 1, condenser 2, receiver 4, flow controlling device 6, and evaporator 8, all arranged in series circuit in the usual manner whereby heat laden low pressure vaporous refrigerant is compressed in the compressor 1 and discharged into the condenser 2 where it gives up heat to a surrounding medium, which may be the surrounding air, and condenses into a liquid which flows into the receiver 4. Liquid refrigerant flows from the receiver under control of the device 6, which is herein shown to be a thermostatic expansion valve but may be of other common types, into the evaporator 8 where it vaporizes thereby abstracting heat from the space 10 to be refrigerated. The invention contemplates the continuous operation of the compressor 1 but at a speed which is just sufficient to withdraw enough of the heat laden refrigerant vapors to maintain a predetermined desired temperature in the refrigerated space 10. As will be brought out later this temperature may be constant or may vary somewhat with change in the amount of heat required to be removed by the evaporator 8.

In the form of the invention shown in Fig. 1, the compressor 1 is powered by means of a gasoline engine 12 through the medium of an endless belt 14. A throttle 16 of the engine 12 controls its speed. The position of the throttle 16 in turn is controlled by means of a control apparatus generally designated 18 having a temperature feeler bulb 20 located at suitable location in the space 10. As the temperature within the space 10 increases the apparatus 18 acts to open the throttle 16 thereby increasing the speed of the engine 12 whereby the compressor 1 will act to withdraw a greater quantity of refrigerant from the evaporator 8 to cause the evaporator to extract more heat from the space 10 and conversely.

In the system shown in Fig. 6 of this application and in the said copending application the associated control apparatus acts in response to

evaporator pressure whereby this pressure is maintained substantially constant. In many applications this latter type of actuation of the control apparatus is sufficient and has met with popular approval by the industry, however, in other circumstances better results may be had when the control apparatus is responsive to temperature.

The apparatus 18 comprises generally a governing portion 22 and a working portion 24 which may be integral as shown in Fig. 1 or the governing portion may be separate as shown in Figs. 3 and 5 and associated with a separate working portion as shown in Fig. 8. The portion 22 comprises a pair of end-to-end arranged hollow housing sections 26 and 28 suitably held together. In the form shown in Fig. 1, a housing section 30 forms an end section for the governing portion 22 and also forms the housing for the working portion 24. Section 28 is provided with a cross wall 32 which has a passageway 34 opening centrally and outwardly of said wall 32 toward the section 26 and which passageway is communicatively connected by means of a small bore conduit 36 with the interior of the bulb 20. The wall 32 is provided with a circular shoulder 38 to which is secured one end of a flexible bellows member 40. The other end of the bellows member 40 is closed by a cap 42 having an outwardly facing circular shoulder 44. An annular ring 46 seats against the shoulder 44 and is held thereto by means of a helical compression spring 48. The spring 48 extends toward an end wall 50 of the housing section 26 and seats against a shoulder on a threaded collar 52 held against rotation by one or more pins 53 slidably received in apertures in the wall 50. The wall 50 is provided with a bearing aperture 54 extending completely therethrough. A threaded adjusting member 56 extends completely through the aperture 54 and is provided with a peripheral shoulder 58 which seats against the wall 50. The external screw threads 60 mate with complementary internal threads of the collar 52 so that when the member 56 is rotated by the calibrated adjusting knob 62 the tension on the spring 48 may be regulated.

The housing section 30 is provided with a chamber 63 having a cylindrical bore portion 64 at its lower end in which is positioned a piston 66. A piston rod 68 is secured at one end to the piston 66 and extends outwardly of the section 30 through its cover 70. The section 30 is also provided with a side wall 72 which acts as an end wall for the housing section 28. The wall 72 is provided with an aperture 74 extending therethrough and in which is positioned a sleeve 76 forming at its opening into the chamber 63 a valve seat 78. A valve member 80 is slidably received within the member 76 and has a valve head 82 which is cooperable with the seat 78 to control flow of high pressure actuating vapor from the receiver 4 through conduit 84 and a passageway 86 in the wall 72 to the chamber 63 above the piston 66. The portion of the valve member 80 intermediate the head 82 and a side wall opening in the sleeve 76 communicating with the passageway 86 is of reduced diameter while the end portion thereof away from the head 82 is of normal diameter to slidably fit within the bore of the sleeve 76 for guiding the member 80. The member 80 extends outwardly of the wall 72 and is threaded secured to a plate member 88. In order to prevent the escape to atmosphere of the fluid which escapes

between the sleeve 76 and member 80 a bellows 90 is provided. The bellows 90 is preferably concentrically arranged relative to the member 80 and is sealed at one end to a dished member 92 clamped between the sections 28 and 30 and at its other end to the plate member 88. A plurality of push rods 94 are each secured at one end portion thereof to the plate member 88 and extend outwardly therefrom through apertures in the wall 32 and are secured at their other end portion to the ring 46.

Referring again to the working portion 24, leakage of fluid to atmosphere between the rod 68 and cover 70 is prevented by a bellows 96 concentrically arranged relative to the piston 66 and having one end sealed to the piston 66 and its other end sealed to an annular member 98 clamped between the cover 70 and the body portion of the section 30. The piston rod 68 is provided with a shoulder 100 which engages the underside of the cover 70 to limit outward movement of the rod 68 and piston 66 under the influence of spring 102 positioned within the bore portion 64 intermediate the end wall thereof and the piston 66. A port 104 is provided in the piston 66 for permitting a regulated flow of fluid past the piston and back to the evaporator 8, such flow being through a passageway 106 and a conduit 108. The passageway 106 not only connects with the bore portion 64 but also with the space between the dished member 92 and end wall 72 whereby this space and the portion of the bore portion 64 beneath the piston 66 will be maintained at the same pressure as that in the evaporator 8. A force transmitting means such as the cable 110 connects the rod 68 to the throttle 16 and acts upon inward movement of the piston 66 into the portion 64 to open the throttle 16 which is continually urged toward closed position by the spring 112.

In operation, high pressure refrigerant vapor is discharged from the compressor 1 into the condenser 2 wherein it is condensed into a liquid which flows to the receiver 4. Liquid from the receiver 4 flows under control of the thermostatic valve 6 to the evaporator 8 whereby the high pressure liquid is reduced in pressure to that of the evaporator 8 after which it evaporates removing heat from the space 10. The heat laden vapor is removed by the compressor 1 and discharged into the condenser 2 for recirculation in the manner described. The rate at which heat is removed from the evaporator 8 will be a function of the speed of operation of the compressor which speed is controlled by means of the apparatus 18.

With the position of the parts of the apparatus 18 as shown, the temperature within the refrigerated space is above that desired and the pressure of the fluid within the bulb 20 has increased to increase the pressure in the chamber surrounded by the bellows 40 so that the end wall or cap 42 thereof has moved outwardly against the force exerted by the spring 48 causing the pins 94 to move the plate member 88 outwardly thereby moving the head portion 82 of the valve 80 into a position to close off fluid flow through the valve ports 78. With no fluid flow through the valve port 78, the pressure across the piston 66 will equalize due to fluid flow through the port 104 thereby permitting the spring 102 to move the piston 66 and the piston rod 68 into its outermost position with respect to portion 64 and the shoulder 100 will be abutting the cap 70. This permits the spring 112 to move the throttle 16

to wide open position whereby the gasoline engine 12 will be operating at full throttle to deliver its maximum power and to drive the compressor 1 at its maximum speed. With the compressor 1 so driven, it will be obvious that it is removing the maximum quantity of refrigerant vapor from the evaporator 8, thereby removing heat from the space 10 at the maximum rate.

As the temperature of the space 10 decreases, the temperature of and the pressure within the bulb 20 decreases reducing the pressure in the chamber surrounded by the bellows 40 permitting the spring 48 to compress the bellows 40, thereby moving the pins 94 and plate member 88 to the right as viewed in Fig. 1. This causes the valve member 80 to open the valve port 78 permitting a predetermined flow of high pressure fluid from the receiver 4 through the conduit 84 and passageway 86 into the chamber 63 above the piston 66. Since the port 104 is of restricted flow capacity, the pressure in the chamber 63 will increase causing the piston 66 to move downwardly and cause the cable 110 to move the throttle 16 toward closed position against the force of the spring 112. The space intermediate the piston 66 and the lower end wall of the bore portion 64 as well as the interior of the bellows member 90 will remain substantially at the evaporator pressure since the passageway 106 is connected through the conduit 108 to the evaporator 8 and has a flow capacity large enough to carry all of the fluid passed by the passageway 104. Movement of the throttle 16 toward closed position will decrease the fuel supplied to the gasoline engine 12 thereby decreasing its output and reducing the speed at which the compressor 1 is driven. This decreases the amount of heat-laden vapor which is removed from the evaporator 8. As the temperature of the space 10 approaches the desired temperature, the temperature of the bulb 20 falls to a predetermined minimum reducing the pressure within the bellows 40 and permitting the spring 48 to move the valve member 80 to its open position in which the pressure differential maintained across the piston 66 is that required to move the piston 66 to its inwardly-most position and the throttle 16 toward minimum fuel flow position. The compressor 1 will then be operating at minimum speed and moving a minimum amount of heat-laden vapor from the evaporator 8.

Conversely, as the temperature within the space 10 increases, the pressure within the bellows 40 will increase causing the head 42 to move toward the left against the force of the spring 48 thereby moving the valve head 82 into a position to reduce fluid flow through the valve port 78. This reduced fluid flow into the chamber 63 decreases the differential in pressure across the piston 66 permitting the spring 102 to move the piston 66 and the rod 68 upwardly so that the spring 112 will move the throttle 16 in an opening direction to increase the output of the gasoline engine 12 and drive the compressor at a higher speed to remove more heat-laden refrigerant vapor from the evaporator 8.

If it is desired to change the temperature at which the space is to be maintained, such may be accomplished by rotation of the knob 62, whereby the force exerted by the spring 48 against the cap 42 may be controlled to determine the pressure within the bellows 40 which is required to position the valve head 82 relative to the valve port 78. If desired, the control knob 62 may be calibrated as shown in Fig. 2, so that rotation

thereof in accordance with the calibration will visually indicate to the operator the approximate temperature at which the space 10 will be maintained.

5 If the change in pressure in the bulb 20 was the only force actuating the valve 80, then the apparatus 18 would operate to provide a substantially constant temperature within the space 10. Since, however, this force is not the only force, the temperature within the space 10 may increase slightly with increasing ambient temperatures. This increase results from the fact that as the ambient temperature surrounding the space 10 increases, more heat will leak into the space 10 and in order to remove this increased heat an increased differential in temperature between the evaporator 8 and the interior of the space 10 is necessary. A decrease in evaporator pressure is reflected in a corresponding decrease in pressure in the bellows 90. Such lowering of this pressure increases the pressure required to be placed in the bellows 40 to move the valve 80 toward closed position to increase the compressor speed.

20 It will now be seen that it is possible by means of varying the relative diameters of the bellows 40 and 90 to proportion the change in temperature within the refrigerated space relative to the change in ambient temperature. If it is desired to keep the space 10 at a substantially constant temperature, then the diameter of the bellows member 40 should be made as large as possible with respect to that of the bellows member 90. If on the other hand, more change in temperature 30 of the space is desired with respect to ambient temperature than the diameter of the bellows 90 should be larger with respect to that of the bellows 40.

35 The control apparatus 18 which is actuated by the temperature of the space 10 and pressure of the evaporating refrigerant within the evaporator 8 for regulating the capacity of the compressor 1, also provides means for controlling the capacity of the compressor so that as the temperature within the space increases away from the desired or set temperature for any reason the capacity of the compressor to remove heat is increased to provide what may be called an increasing recovery factor. Conversely, as the actual space 40 temperature approaches the desired or set temperature the recovery factor may decrease so that the temperature in the space is not lowered below the desired temperature. The rate of change in the recovery factor is to a large extent determined by the relative areas of the bellows 40 and 90, the rate of increase in exerted force of the spring 48 due to a collapsing thereof and the rate of change in fluid flow through the valve port 78 with movement of the valve member 80. Generally it may be assumed that the recovery factor should be high so that the temperature of the space will be brought to the desired temperature as rapidly as possible. In such event slight increases in temperature of the bulb 20 should provide for relatively great changes in fluid flow through the port 78 and the area of the bellows 90 should be small so that any lowering of the evaporator pressure will not tend to close the port 78.

45 50 55 60 65 70 75 Under other conditions it may be desirable to restrict the magnitude of the recovery factor to prevent undue lowering of the evaporator temperature and pressure and in such event the area of the bellows 90 might be increased to provide a throttling movement of the valve member 80

relative to the port 78 upon an undesired lowering of the evaporator pressure. The particular relationships will depend upon the operating characteristics desired for the particular installation.

As the space temperature approaches the desired temperature the engine 12 will be reduced in speed to reduce the capacity of the compressor 1 so that it cannot lower the temperature of the space 10 below that desired. It will now be apparent that the invention provides for operating a refrigerating system with any desired rate of recovery and further for operating the system to prevent the temperature of the space from being lowered below the desired temperature.

Referring now to Fig. 3 which shows a modified form of the control mechanism or apparatus 18a, it will be apparent that this apparatus 18a may be substituted for the governing portion 22 of Fig. 1, and in such event, a separate working portion or cylinder 24a such as shown in Fig. 8 would be associated therewith for controlling the engine throttle 16. The apparatus 18a distinguishes from the apparatus 18 in that the working portion 24 of the apparatus 18 has been removed and a casing section 30a has been substituted therefor. The casing 30a comprises means to close the opposite end of the casing section 28 from that closed by the casing section 26a and is provided with an inlet passageway 86a adapted to be connected to receive high pressure vapor from the receiver 4 for controlling flow therefrom to the passageway 120 which may be connected in fluid flow relation with the portion of the chamber 63a above the piston 66a, Fig. 8. In the modified form shown in Figs. 3 and 4, the poppet-type valve 80 has been replaced by a sleeve-type valve 80a which is reciprocal within a sleeve 76a carried within the casing section 30a. The sleeve 76a is provided with radial passageways aligned respectively with the passageway 86a and the passageway 120. The valve 80a is provided with a circumferential groove or slot 122 which with the valve 80a in one position aligns itself with the radial passageways of the sleeve 76a and which is movable outwardly of this aligned position to restrict and finally to cut off flow of fluid from the passageways 86a to the passageway 120. As the valve 80a moves under control of the bellows 40a, the flow of high pressure fluid from the receiver 4 to the working cylinder 24a is controlled substantially in the same manner as the fluid flow was controlled by the apparatus 18 upon movement of the valve member 80. In order to permit the escape of the gaseous fluid which may pass downwardly between the valve member 80a and the sleeve 76a, the section 30a is provided with a branch passageway 124 (Fig. 3) which communicates with the passageway 106a connected to the evaporator by means of conduit 108a. The passageway 120 is arranged to be communicatively connected to an inlet port 126 of the working cylinder 24a.

It will be obvious from the description of the portion 24a that as the flow of fluid passed by the valve member 80a increases, the pressure in the chamber 63a above the piston 66a will increase causing the piston 66a to move downward whereby its piston rod 68a will move downwardly to cause the throttle 16 to move toward closed position. The space below the piston 66a is connected to the low pressure side of the refrigerating system by means of a conduit attached to the outlet 128 thereof for discharge of the fluid passed by the passageway or port 104a. It will be obvious

with the form of control shown in Figs. 3 and 4, when associated with the working portion, shown in Fig. 8, that it will be possible to locate the control apparatus 18a closely adjacent the space 5 to be refrigerated and the working portion 24a closely adjacent the throttle of the engine of which it is associated substantially as shown in Fig. 6. Under some installation conditions in which there is quite a distance between the refrigerated space and the condensing unit, this type of apparatus may have certain advantages over the form shown in Fig. 1.

In Fig. 5, there is shown a still further modified form of apparatus 18b which may be used 15 in place of the apparatus 18a and which comprises housing sections 150 and 152 between which there is clamped a plate member 154. The housing section 152 contains the valve member 80b having the head 82b for controlling the flow of high pressure vapor from the inlet passageway 86b to the outlet passageway 120b. The valve member 80b is concentrically positioned within a sleeve 76b and has its upper end threadedly secured to a cap member 156. The platelike member 154 has a central aperture therethrough through which the valve member 80b extends. A bellows 90b is arranged concentric to the valve member 80b and is sealed at its lower end to the platelike member 154 and at its 20 upper end to the cap member 156. A passageway 34b within the plate 154 opens upwardly therefrom exterior to the bellows 90b and within a second bellows 40b which is also arranged concentrically with the bellows 90b. The bellows 90b is sealed at its lower end to the plate member 154 outwardly of the opening of the passageway 34b and sealed at its upper end to the cap member 156. The apparatus 18b shown in Fig. 5 operates substantially like the apparatus 18a as already described and is arranged to have the passageway 86b connected to the receiver 4 by a conduit (not shown), the passageway 106a connected to the evaporator, and the passageway 120b connected to the passageway 126 of the cylinder 24a.

In Fig. 6 there is shown a refrigerating system having a gasoline engine 12, a compressor 1, a space 10 to be refrigerated, an evaporator 8 within the space, a thermostatic expansion valve 6, a condenser 2 and a receiver 4, all operatively connected together in the usual manner by means of conduits or other fluid conveying means. In this system, the apparatus 18c is not provided with a temperature bulb similar to the bulb 20 but is actuated by the evaporator pressure communicated thereto by the conduit 200. High pressure fluid for actuation of the cylinder 24a, Fig. 6, is communicated to the apparatus 18c by the conduit 108 and a conduit 121 conveys the fluid from the apparatus 18c to the cylinder 24a. The controlling apparatus 18c is more clearly shown in Fig. 7. The operation of the system in Fig. 6 is substantially the same as that of the system shown in my said copending application, but the particular form of controlling apparatus as shown in Figs. 7 and 8, is believed to be an improvement over the form of apparatus shown in my said copending application. In this form of apparatus, the pressure in the evaporator is 60 communicated to the interior of the bellows 90c by means of a conduit 200 open at one end to the evaporator 8 and at the other end to a passageway 202 of the apparatus 18c. The upper end of the bellows is closed by means of a cap member 156c, the upward movement of which

is opposed by means of a compression spring 48c. The force exerted by the spring 48c may be controlled by means of the knob 62c similarly as was the force exerted by the spring 48. High pressure fluid from the receiver 4 is communicated by means of a conduit 198 to the inlet passageway 204 of the apparatus 18c and its flow outwardly through the outlet 206 of the apparatus 18c is controlled by means of the position of the valve 80c with respect to the valve port 78c. The outlet 206 is connected by means of a conduit, or other fluid conveying means to the inlet 126 of the working portion of cylinder 24a for control of the throttle.

Figs. 9 and 10 illustrate a still further modified form of the control apparatus for use in the system of Fig. 6 which is quite similar to the apparatus 18 used in connection with the system of Fig. 1 insofar as the working portion 24d is formed integrally with the controlling apparatus 18d. The apparatus of Fig. 9 is similar to the apparatus of Fig. 7, in that there is no provision therein for the application of pressure communicated thereto as by the bulb 20 of the system of Fig. 1. It will be noted from a study of Fig. 10 that the working portion 24d is substantially identical with the working portion 24a shown in Fig. 8, except that it is directly connected with the control apparatus, whereby the same may be used as a single unit.

The modification shown in Figs. 11 and 12 of the apparatus 18 is substantially the same as the apparatus 18d shown in Fig. 7, except that instead of the poppet-type valve a sleeve-type valve similar to that shown in connection with the modification shown in Fig. 3 is provided. In the modification shown in Fig. 11, the means for attaching the apparatus 18b, 18c, or 18d to a supporting member 300 is shown. It will be apparent that the casing sections 26b, 26c, or 26d are provided with external threads 302 upon which may be threaded a nut 304. The apparatus is inserted through an aperture 306 in the supporting member 300 after which an annular ring 308 is slid over the upper end of the casing sections 26b, 26c, or 26d and is held against outward movement by means of a snap ring 310. The nut 304 is then screw threaded along the threads 302 whereby the nut clamps the annular ring 308 to the support 300. The control knob 62e may then be inserted in place and held thereto by means of the spring detent 312.

This application is directed toward an improvement over the invention shown and claimed in my said copending application in that this application contains claims directed toward an improved control mechanism and also claims directed toward an improved controlling system for maintaining the temperature in a refrigerated space within predetermined limits by means of a constantly operating condenser unit.

What is claimed and what is desired to be secured by United States Letters Patent is as follows:

1. An apparatus for controlling a refrigerating system having a low pressure portion and a high pressure portion comprising a casing, a pressure sensitive element within said casing having a portion movable as a function of the pressure on said element, means responsive to temperature of a space to be refrigerated for controlling the pressure on said element, means providing a fluid flow passageway adapted to be connected between said system portions, a pressure sensitive actuator sensitive to the pressure in said passageway,

controlling means operatively connected to said actuator for actuating thereby as a function of the pressure applied to said actuator, valve means controlling flow of fluid through said passageway for controlling the fluid pressure in said actuator, and means operatively connecting said element portion and said valve means whereby said valve means is operable to control the fluid pressure in said actuator as a function of the temperature of the space and independently of the pressure in said low pressure portion.

2. An apparatus for controlling a refrigerating system having a low pressure portion and a high pressure portion comprising a casing, a sealed fluid pressure system separate from said refrigerating system and responsive to temperature of a space to be refrigerated and including a pressure sensitive element within said casing, means providing a fluid flow passageway adapted to be connected between said refrigerating system portions, a pressure sensitive actuator sensitive to the pressure in said passageway, controlling means operatively connected to said actuator for actuating thereby as a function of the pressure applied to said actuator, valve means controlling flow of fluid through said passageway for controlling the fluid pressure in said actuator, and means operatively connecting said element portion and said valve means whereby said valve means is operable to control the fluid pressure in said actuator as a function of the temperature of the space.

3. An apparatus for controlling a refrigerating system having a low pressure portion and a high pressure portion comprising a casing having a wall with an aperture therethrough and a pressure chamber, a valve controlling flow through said aperture, a sealed fluid pressure system responsive to the temperature of a space to be cooled and having a pressure sensitive element within said casing, means operatively connecting said element and said valve, means including said aperture and said chamber and providing a fluid flow passageway adapted to be connected between said system portions, a movable pressure sensitive wall for said chamber and movable in response to pressure in said chamber, and controlling means operatively connected to said movable wall whereby said controlling means is actuated as a function of the pressure acting on said movable wall.

4. The combination of claim 3 in which said pressure sensitive wall limits flow through said passageway providing means and is provided with a restricted fluid flow orifice to permit a limited flow of fluid past said pressure sensitive wall.

5. An apparatus for controlling a refrigerating system having a low pressure portion and a high pressure portion comprising, a casing having a pair of casing chambers separated by a dividing wall, said wall being provided with a first passageway extending therethrough and opening outwardly at opposite sides of said wall into said chambers, said wall having a second passageway communicating with and extending laterally of said first passageway intermediate its ends, a valve cooperable with a first portion of said first passageway which opens outwardly of said wall into one of said chambers for controlling fluid flow through said second passageway, said valve having a stem extending through a second portion of said first passageway which opens outwardly of said wall into a second of said chambers, a sealed fluid pressure system responsive to the temperature of a space to be cooled and hav-

ing a pressure sensitive element in said second chamber, a fluid seal within said second chamber and sealing said first passageway against flow of fluid into said second chamber, means including said seal for operatively connecting said valve and said element, fluid conveying means including said first and second passageways and said first chamber for providing a fluid flow passageway adapted to be connected between said system portions, and a movable pressure sensitive wall for said first chamber and movable in response to pressure within said chamber.

EDWARD F. DICKIESON, JR.
